UNITED STATES PATENT OFFICE.

EDMUND PAUL EHRLINGER, OF JANEVILLE, WISCONSIN.

PORTABLE SLUG, RULE, AND BORDER STANDARD.

Application filed March 23, 1923. Serial No. 627,115.

To all whom it may concern:

Be it known that I, EDMUND PAUL EHRLINGER, a citizen of the United States, and resident of Janesville, in the county of Rock 5 and State of Wisconsin, have invented certain new and useful Improvements in Portable Slug, Rule, and Border Standards; and I do hereby declare that the following is a full, clear, and exact description thereof.

10 This invention relates to a portable unit or standard for printers, which is designed to contain material needed by printers.

15 Printing establishments are usually relatively crowded and in an effort to economize space, some general or main supply of material is maintained for the compositors. This necessitates numerous trips to the source of supply and causes unnecessary confusion.

20 This invention is designed to overcome the above noted defects and objects of such invention are, therefore, to provide a portable standard for the rule cases, slugs, border strips, and similar material, which can 25 be readily moved about to the various compositors, which is so constructed that it permits choosing from a wide range of material, which presents such material in a readily accessible manner, which occupies 30 a small amount of floor space, and which is equipped with universally mounted electric lights which may be adjusted to illuminate any portion of the apparatus.

35 An embodiment of the invention is shown in the accompanying drawings, in which:—

Figure 1 is a side elevation of the standard.

Figure 2 is a sectional view on the line 2—2 of Figure 1.

40 Referring more particularly to the drawings, it will be seen that the standard comprises a frame work which is preferably formed of tubular sections with connecting fittings and may conveniently be formed of 45 pipe, or similar material. It comprises a bottom horizontal bar 1, a corresponding upper horizontal bar 2, end uprights 3 and an intermediate upright 4. The end uprights and the bottom horizontal member 50 join transverse end members 5 which carry supporting rollers 6 in a spaced manner, so as to secure not only longitudinal stability, but also lateral stability.

55 A plurality of supporting brackets 7 are secured to the three uprights and, if desired, may be formed in a series, each joined by

a vertical portion 8 (see Figure 2) and such vertical portion may be secured by riveting, bolting, or otherwise to the respective upright. These brackets are provided with a 60 supporting slanting, or inclined surface 9 terminating in lower supporting lips 10, as may be most readily seen from Figure 2.

A plurality of open shallow trays 11, 12 and 13 are removably positioned upon the 65 inclined surface 9 of the brackets and are supported by the terminal lips, or hooks 10. These trays are adapted to support compositors' material. For instance, leads or slugs may be carried in the lowest tray and may 70 extend the full width thereof and the shorter borders may be carried in the intermediate trays and in the uppermost trays the printers' rule cases or sets, such trays being conveniently made of a length to accommodate 75 the requisite number.

Preferably, a pair of lamps are mounted upon brackets 15 and are joined by means of universal connections 16 and 17 to such brackets and to the frame work, or standard, so that the lamps may be turned or moved in any desired manner to illuminate any portion of the trays, or to generally illuminate opposite sides of the standard. If desired, the lamps may be wired to a socket 80 18 secured in any desired position as, for instance, in the central fitting of the frame work, so that no trailing cord need necessarily be had when the device is moved from place to place.

90 In printing establishments it is customary to keep the supply of material for the compositors' use at a definitely fixed place, so that when the compositor needs this type of material, he is compelled to leave the 95 place at which he is working and secure it from its fixed source of supply. However, with the present portable standard disclosed herewith, this needless waste of time and effort is avoided, as the device may be readily pushed to a position adjacent the compositor and all of the material that he will need is then presented in a readily accessible manner. It frequently happens that the light distribution is so arranged that it 100 is excellent for the exact place at which the compositor is working, but when the standard is moved into a position adjacent the compositor, it frequently happens that such standard would not ordinarily be well 105 illuminated. For this purpose, the universal mounted lamps are provided and any 110

portion of the standard, or each side generally may be fully and adequately illuminated, minimizing the time required to locate the particular material desired.

5 Obviously, the frame work may be varied in its exact formation. For instance, braces may be used from different portions thereof and, as illustrated in Figure 2, diagonal braces 19 may connect the vertical standards 3 with the horizontal portions 5. These braces may be formed as separate members or, if desired, may be formed integral with the portions 8 of the brackets.

10 It will thus be seen that a portable standard has been provided for printers' use which, although carrying quite a material load, may be readily moved from point to point, which is adapted for independent illumination and which presents all of the 15 extra material in a readily accessible manner.

20 I claim:

A portable support for compositors' material comprising a vertical frame work having end bars and an intermediate bar extending vertically upwardly and joined adjacent their upper and lower ends, a bracket secured on opposite sides of each of said bars, said brackets furnishing a plurality of downwardly slanting faces arranged one under the other with the upper end of one 25 face spaced below the lower end of the next face, outwardly extending lugs carried by said brackets adjacent the lower ends of each of said faces, and a plurality of elongated trays supported by said faces and said 30 brackets.

25 In testimony that I claim the foregoing I have hereunto set my hand at Janesville, in the county of Rock and State of Wisconsin.

EDMUND PAUL EHRLINGER.
